UNITED STATES PATENT OFFICE.

GERALD W. HART, OF WEST HARTFORD, CONNECTICUT, ASSIGNOR TO THE HART MANUFACTURING COMPANY, OF HARTFORD, CONNECTICUT, A CORPORATION OF NEW JERSEY.

SWITCH.

1,149,755.

Specification of Letters Patent. Patented Aug. 10, 1915.

Application filed May 1, 1914. Serial No. 835,612.

To all whom it may concern:

Be it known that I, GERALD W. HART, a citizen of the United States, residing at West Hartford, county of Hartford, State 5 of Connecticut, have invented certain new and useful Improvements in Switches, of which the following is a full, clear, and exact description.

My invention relates to improvements in 10 switches, and has for its object to provide a simple and efficient switch for controlling electric circuits, and is particularly adapted for controlling the circuits, such as those of motors, for starting automobiles.

It further has for its object to produce a 15 switch which is durable in construction and easy to manufacture.

The following is a description of an embodiment of my invention, reference being 20 had to the accompanying drawings, in which—

Figure 1 shows a vertical central section of the switch with the parts in open position. Fig. 2 shows a similar view with the 25 parts in closed position. Fig. 3 shows an end elevation of the casing with the operating rod in section on the line 3—3 Fig. 1. Fig. 4 is a plan view of the switch with the cover removed, *i. e.*, on the line 4—4 Fig. 1. Fig. 5 is a perspective detail of one of the 30 elements.

Referring more particularly to the drawings, 1 is a switch casing having a cover 2 secured thereto by screws. The inner wall 35 of the switch casing carries terminals 3—4, one of which at least is insulated from the casing. Where one terminal of the battery is not grounded, both of the terminals 3—4 should be insulated as shown at 5. The 40 inner wall of the casing also carries a projection 6 having a bore 7 in which slides a plunger 8 carrying on its outer end a laminated switch arm 9 secured thereto in a proper manner. Where one terminal of the 45 source of current is not grounded, this laminated switch arm should be insulated from its support by insulation 10. Between the inner end of the case and switch arm is a spring 11, by reason of which the switch arm 50 tends to move to open position. The lower wall of the casing carries a headed stud 12, upon which the notched end 13 of a lever 14, loosely fits the central portion of which lever bears upon the outer end of the plunger 8. This lever is bifurcated and has an

elongated opening 15 and two bifurcations or arms 16 and downwardly inclined portions 17, which provide a two part cam surface. 18 is a sliding rod mounted in bearings in the walls of the casing 1 and provided with an operating connection or handle. This rod lies between the bifurcations and carries a pin 19 which projects on each side thereof so as to make engagement with the arms or bifurcations 16 of the lever 14, 60 and also carries a stop 20 shown in the form of a screw engaging a screw-threaded hole in the rod 18. The inner end of this stop lies within the elongated opening 15 and bears against the abutments formed by the 65 ends thereof, constituting a stop for the rod 18 and limiting its movement in each direction. The pin 19 engages the cam surface 17 and when the sliding rod 18 is moved upward, causes the lever 14 to move inward 70 about its fulcrum 12 so as to move the switch arm 9 into engagement with the terminals 3 and 4, thus closing the switch. When the switch is in closed position, as shown in Fig. 2, and the rod is moved downward, the 75 switch arm is released and is then moved to open position by the action of the spring 11. Where a snap action is desired the pin 19 is movably mounted in a slot 18' in the rod 18. In order to keep the pin 19 in alignment it is passed through a sleeve 19' which surrounds and slides freely on the rod 18. The arms 16 embrace the rod 18 and sleeve 19' so that both ends of the pin 19 act upon 80 the lever 14. 85

Plates 9—9² surround the plunger and are on opposite sides of the switch arm 9. The plate 9² is provided with upwardly projecting flanges 9³ which engage the two sides of the lever 14 and keep the switch 90 arm in alignment with the contacts 3 and 4.

In operating the switch the rod 18 is moved in one direction or the other, whereupon the switch opens or closes. On account of the lost motion between the pin 19 and the rod 18, the switch opens with a 95 snap action.

As will be evident to those skilled in the art, my invention admits of modifications without departing from the spirit thereof or 100 the scope of the appended claims.

What I claim is—

1. In a switch the combination of a base, terminals supported thereby, a switch arm for engaging and disengaging said terminals 110

- and normally tending to move away therefrom, a bifurcated cam lever for actuating said switch arm, the fulcrum of which lever is fixed relatively to said base, a rod sliding 5 in fixed bearings and embraced by the bifurcations of said lever, and a pin carried by said rod and having lost motion relatively thereto, said pin engaging the bifurcations of said cam lever.
- 10 2. In a switch the combination of a base, terminals supported thereby, a switch arm for engaging and disengaging said terminals and normally tending to move away therefrom, a bifurcated cam lever for actuating 15 said switch arm, the fulcrum of which is fixed relatively to said base, a rod sliding in fixed bearings and embraced by the bifurcations of said lever, and a pin carried by said rod, said pin engaging the bifurcations 20 of said cam lever.
3. In a switch the combination of a casing, terminals supported by one wall thereof, a movable switch arm for engaging and disengaging said terminals and tending to 25 move away therefrom, an elongated cam member having one end supported by said casing for moving said switch arm, and a sliding rod carried by said casing and provided with means for engaging said cam 30 member to move said member and said switch arm toward said terminals.
4. In a switch the combination of a casing, terminals supported by one wall thereof, a movable switch arm tending to move 35 away from said terminals, a cam lever engaging said switch arm and having one end fulcrumed on said casing and a sliding actuating member provided with means engaging said lever to move said lever and said switch arm toward said terminals.
- 40 5. In a switch the combination of a casing, terminals supported by one wall thereof, a movable switch arm tending to move away from said terminals, a cam lever en-
- gaging said switch arm and having one end 45 fulcrumed on said casing and a sliding actuating member provided with means engaging said lever to move said lever and said switch arm toward said terminals, said lever being provided with abutments and 50 said sliding member being provided with a stop engaging said abutments so as to limit the movement of said member.
6. In a switch the combination of a casing, terminals supported by one wall thereof, a movable switch arm tending to move 55 away from said terminals, a cam lever engaging said switch arm, said casing and lever being, one provided with a projection and the other a portion surrounding said 60 projection at the fulcrum of said lever, and a sliding actuating member provided with means engaging said lever to move said lever and said switch arm toward said terminals, said lever being easily removable from said 65 casing.
7. In a switch the combination of a casing, terminals supported by one wall thereof, a movable switch arm tending to move away from said terminals, a cam lever engaging 70 said switch arm and having one end fulcrumed on said casing and a sliding actuating member provided with means engaging said lever to move said lever and said switch arm toward said terminals, said 75 lever being provided with abutments and said sliding member being provided with a stop engaging said abutments so as to limit the movement of said member, said lever and said switch arm being provided one 80 with projections and the other with lateral surfaces engaged thereby for holding said switch arm in alinement with said terminals.
